UNITED STATES PATENT OFFICE

2,461,530

ROCK DRILL

John C. Curtis and Elmer G. Gartin, Claremont, N. H., assignors to Joy Manufacturing Company, a corporation of Pennsylvania

Application July 2, 1943, Serial No. 493,240

10 Claims. (Cl. 121—32)

1

This invention relates to rock drills and more particularly, but not exclusively, to improvements in a hammer rock drill of the stoper type.

An object of the present invention is to provide an improved rock drill of a novel design. Another object is to provide an improved chuck mechanism for a rock drill having a novel arrangement of parts whereby ruggedness and relatively long life of the parts are assured. Yet another object is to provide an improved water and dirt guard for the chuck of a rock drill so that access of foreign matter to the bearing surfaces of the chuck is prevented. Still another object is to provide an improved rock drill having novel combinations and arrangements of parts. These and other objects and advantages of the invention will, however, hereinafter more fully appear in the course of the following description.

In the accompanying drawings there is shown for purposes of illustration one form which the invention may assume in practice.

In these drawings:

Fig. 1 is a view in longitudinal vertical section through a rock drill constructed in accordance with an illustrative embodiment of the invention.

Fig. 2 is a sectional view similar to Fig. 1, showing the moving parts in a different position assumed during normal running of the drill.

Fig. 3 is a fragmentary sectional view taken on the plane of Fig. 2, showing the hammer piston in a forward cushioned position.

Fig. 4 is a cross sectional view taken substantially on line 4—4 of Fig. 3.

Fig. 5 is an enlarged detail sectional view taken on the plane of Fig. 2, showing the piston in its forward position during normal running of the drill.

Fig. 6 is a perspective view of the water and dirt guard.

In this illustrative embodiment of the invention there is shown a hammer rock drill which is preferably of the stoper type for drilling upwardly directed holes and provided with a conventional pneumatic feed leg, not shown. Features of the invention may be embodied in rock drills of other types as will be evident.

The rock drill may be of the same general design as that disclosed in our copending application Serial No. 493,086, filed July 1, 1943, and including a pressure fluid motor, generally designated 1, which may be generally similar to that disclosed in our copending application Serial No. 475,782, filed February 13, 1943. The pressure fluid motor 1 includes a motor cylinder 2 having a bore 3 containing a reciprocating hammer pis-

ton 4. The hammer piston has an impact surface 5 formed on an impact member 6 fixed within a bore 7 within the forward portion of the piston. This piston impact surface is adapted to strike against a tappet or striking block 8 which transmits the blows of the piston to the shank of a drill steel 9. Attached by bolts 10 to the forward end of the motor cylinder is a chuck housing 11 having stepped bores 12 and 13 joined by an inclined shoulder 14. The front end of the chuck housing has an inwardly directed annular flange 15 providing a rearwardly facing shoulder 16. Journaled within the chuck housing bores is a driver sleeve 17 having a forwardly facing inclined shoulder 18 engaging the shoulder 14 at the juncture of the bores 12 and 13. Threadedly secured within the sleeve bore is a chuck sleeve 19 provided with an external annular flange 20 interposed between the shoulder 16 on the chuck housing and the front end surface 21 of the driver sleeve 17 in the manner shown. Threadedly secured within the chuck sleeve bore is a chuck member 22 having a socket 23 for receiving the steel shank. The socket 23 is preferably polygonal in cross section, corresponding to the cross section of the steel shank so that the steel is rotated with the chuck member while being free to reciprocate with respect thereto in a well known manner.

20 In this improved construction a dirt and water guard or chuck shroud 24 is provided to prevent entry of foreign matter to the bearing surfaces between the chuck parts. This guard is of circular shape and has an inwardly directed front flange 25 rigidly clamped between the forward end surface 26 of the chuck sleeve 19 and an external annular flange 27 on the chuck member 22. This guard has a circular skirt portion extending over the forward ends of the chuck sleeve and chuck housing, for tightly engaging the exterior periphery of the chuck housing at 28 to provide a dirt seal. This guard shrouds the forward ends of the chuck housing and the chuck sleeve so that access of dirt and water to the bearing surfaces is precluded. Of course the chuck sleeve, chuck member and guard are rotated together during steel rotation.

25 Formed externally on the hammer piston 4 are straight flutes or grooves 29 which cooperate with straight keys or splines 30 on a chuck nut 31 keyed within the driver sleeve so that rotary motion of the hammer piston is transmitted to the driver sleeve and thence to the drill steel. Arranged within a rear head member 32, held in position within the rear end of the cylinder by a rear head block 33, is a ratchet ring 34 engaged

2

by usual spring-pressed pawls 35 carried by a pawl carrier 36. This pawl carrier is integrally secured to a spirally grooved rifle bar 37 which extends forwardly into the rear end of the cylinder bore and engages a rifle nut 38 secured within the hammer piston. As the hammer piston moves forwardly to effect its working stroke, i. e. to strike a blow on the tappet 8, the pawls of the carrier slip over the ratchet teeth, thereby permitting unimpeded piston movement. Upon rearward movement of the hammer piston, the pawls engage the ratchet teeth to hold the rifle bar against rotation so that, due to the spiral groove interlocking connection, a rotary motion is imparted to the piston, and this rotary motion is transmitted to the drill steel through the chuck. As is usual in rock drills of the type disclosed, cleansing liquid may be conducted to the drill steel bore to effect cleansing of the drill hole, and the tube provided for this purpose extends axially from the rear head block into the motor cylinder and through the hammer piston and tappet into the drill steel bore. In distinction from other constructions, the tube is a close sliding fit for the openings in the impact member 6 and the striking block 8. During the drilling operation, the water emerging from the drill hole runs down over the forward portion of the chuck, and the guard 24 directs the water and dirt over the chuck housing externally of the chuck.

The tappet 8 is mounted for reciprocatory movement in a bore 40 in the chuck sleeve 19, and the chuck sleeve has a reduced rearwardly projecting portion 41 having a bore 42 which receives the body of the tappet in the manner shown. The tappet projects rearwardly from the rear end of the chuck sleeve into a position to be struck by the hammer piston. Surrounding the rearward reduced portion 41 of the chuck sleeve within the driver sleeve 17 is an annular chamber 43 into which the forward end of the hammer piston is adapted to enter during its reciprocation as will later be explained.

The rear end of the cylinder bore is closed by a rear head plate 44, and arranged between this head plate and the rear head member 32 is a valve chest 45 having a valve chamber containing a pair of cooperating relatively movable fluid distributing valves 46 and 47. Carried by the rear head block 33 is a throttle valve 48 which may control the flow of pressure fluid through a supply passage 49 to the valve chamber internally of the valves. Leading from the opposite ends of the valve chamber are fluid supply passages 50 and 51 for conducting pressure fluid, under the control of the valves, to the opposite ends of the cylinder bore to effect reciprocation of the hammer piston. The piston-controlled cylinder exhaust is indicated at 52. The pressure fluid may flow in the manner fully described in the copending application Serial No. 475,782 above referred to, to the chamber 43 at the forward end of the hammer piston from the front end of the cylinder bore through the piston flutes to assist in returning the hammer piston after it delivers its impact blow to the tappet 8. Throwing passages 53 and 54 controlled by the piston connect the cylinder bore with the valve chamber so that the valves may be thrown automatically into their different operating positions as the hammer piston reciprocates. This valve structure and the fluid supply and throwing passages are described in the above mentioned copending application Serial No. 475,782.

The exterior of the rearward portion of the

chuck sleeve projection 41 is tapered at 55 (Fig. 5), and the front edge of the piston surrounding the bore 7 therein is chamfered or rounded-off at 56 so that during normal operation of the drilling motor the forward end of the hammer piston and the chuck sleeve projection never come into substantial contact, or if contact should occur, it would be relatively slight (see Fig. 2). Thus very little wear of the surfaces at 57 and 58 occurs during normal operation of the drill. Pressure fluid flowing from the cylinder bore through the piston flutes to the annular chamber 43 also enters the piston bore 7 at the rear of the chuck sleeve projection so that some cushioning of the piston movement takes place although comparatively little resistance to the forward movement of the piston is present at that time. Should the hammer piston be driven forwardly into a more advanced forward position, for instance, in the event the drill steel strikes a pocket, the tappet is driven forwardly into the chuck sleeve bore as shown in Fig. 3 and the surfaces 57 and 58 (Fig. 5) move into contact, thereby providing a seal and trapping the fluid in the piston bore to provide a substantial fluid cushion for the piston, thus preventing contact of the forward end of the piston with the chuck parts. Since during normal operation of the drilling motor little wear of the surfaces 57 and 58 occurs, a relatively fluidtight seal is provided to prevent substantial fluid leakage from the cushion. Of course, there is no substantial loss of the cushion, both because of the maintained surface contact between the impact surface 5 and the rear end of the striking block 8, and because the close fits around the water tube would prevent serious leakage in the short times available, in any event. If the drill motor is run without a steel, the striking block may move up into contact with the inner end of the chuck bushing, and the forward end of the hammer motor piston may move forwardly almost into contact with the inner end of the chuck sleeve at its extremes of forward movement, and under these circumstances the close fits around the water tube will safely maintain the necessary cushion pressure against escape.

As a result of this invention an improved chuck mechanism is provided having a novel arrangement of parts providing adequate bearing surfaces, whereby ruggedness and relatively long life of the parts are assured. By the provision of the novel dirt and water guard access of foreign matter to the chuck bearing surfaces is prevented. The improved drilling motor structure embodying the novel cushioning arrangement disclosed affords an improved and extremely effective cushioning of the hammer piston. Wear of the sealing surfaces of the cushion is substantially eliminated during normal motor operation, due to the novel arrangement of parts, so that when the sealing surfaces come into substantial contact a very effective trapping of the cushioning fluid is possible. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a rock drill, a chuck mechanism for a drill steel comprising a chuck housing, a chuck sleeve rotatable in said housing, a chuck member detachably secured to said sleeve for rotation therewith and adapted to receive the shank of a drill steel, and a dirt and water guard rigidly clamped between said chuck sleeve and chuck member for rotation therewith and having portions enclosing the forward portions of said chuck sleeve and said housing.

2. In a rock drill, a chuck mechanism for a drill steel comprising a chuck housing, a chuck sleeve rotatable in said housing, a chuck member detachably secured to said sleeve for rotation therewith and adapted to receive the shank of a drill steel, and a dirt and water guard rigidly clamped between said sleeve and chuck member and enclosing the forward portion of said housing.

3. In a rock drill, a chuck mechanism for a drill steel comprising a chuck housing, a chuck sleeve rotatable in said housing, a chuck member detachably secured to said sleeve for rotation therewith and adapted to receive the shank of a drill steel, and a dirt and water guard having an annular flange clamped between said sleeve and chuck member and enclosing the forward portion of said housing.

4. In a chuck mechanism for percussive rock drills, a driver sleeve having a reduced forward bore and an enlarged rearward bore, a chuck sleeve arranged in said front bore of said driver sleeve and having a portion projecting rearwardly into said rear bore, said chuck sleeve having a bore, a chuck member secured in said chuck sleeve bore and adapted to receive and support the shank of a drill steel, said chuck sleeve bore extending rearwardly of said chuck member, said chuck sleeve having a reduced portion projecting rearwardly into said enlarged rearward bore, said rearwardly extending bore of said chuck sleeve and said reduced chuck sleeve portion adapted to receive and reciprocably guide a tap-pet for transmitting blows to the shank of the drill steel.

5. In a chuck mechanism for percussive rock drills, a driver sleeve having a bore, a chuck sleeve arranged in said sleeve bore and having a bore, a chuck member secured in said chuck sleeve bore and adapted to receive and support the shank of a drill steel, said chuck sleeve bore extending rearwardly of said chuck member, said chuck sleeve having a reduced projection extending rearwardly within said driver sleeve bore and having a reduced bore, said rearwardly extending bore of said chuck sleeve and said reduced bore in said rearward projection of said chuck sleeve adapted to receive and reciprocably guide a tap-pet for transmitting blows to the shank of the drill steel.

6. In a rock drill, a chuck mechanism for a drill steel comprising a chuck housing, a chuck sleeve rotatable in said housing and projecting outwardly from the forward end thereof, a chuck member secured to said sleeve for rotation therewith and adapted to receive the shank of a drill steel, said chuck member projecting forwardly from said sleeve, and a dirt and water guard enclosing the forward portions of said sleeve and housing, said guard having an inwardly directed annular flange rigidly clamped between the front end of said sleeve and said chuck member and providing a central opening through which said chuck member projects.

7. In a rock drill, a chuck mechanism for a drill steel comprising a chuck housing, a chuck sleeve rotatable in said housing and projecting outwardly from the forward end thereof, a chuck member secured to said sleeve for rotation therewith and adapted to receive the shank of a drill steel, said chuck member projecting forwardly from said sleeve, and a dirt and water guard enclosing the forward portions of said sleeve and housing, said guard rigidly secured between said sleeve and chuck member and having stepped front and rear axial bores, the forward reduced bore receiving the forward portion of said sleeve and the rearward larger bore receiving the forward portion of said housing, and said guard having a front central opening of smaller diameter than said bores and through which said chuck member projects.

8. In a chuck mechanism, a chuck housing, a rotatable chuck sleeve journaled in said housing and projecting forwardly therefrom, a chuck member secured in said sleeve for rotation therewith and projecting forwardly from said sleeve, and a dirt and water guard enclosing the forward portion of said chuck housing and having an inwardly directed front annular flange surrounding said chuck member and rigidly clamped between said sleeve and said chuck member, said guard serving to prevent the access of dirt and water to the bearing between said sleeve and chuck housing.

9. In a chuck mechanism for percussive rock drills, a driver sleeve having stepped front and rear axial bores of which said front bore is the smaller, a chuck sleeve secured in the smaller front bore of said driver sleeve, a chuck member secured in said chuck sleeve and adapted to receive and support the shank of a drill steel, said chuck sleeve having a portion projecting rearwardly into the larger rear bore of said driver sleeve and having its outer periphery spaced inwardly from the walls of the larger bore to provide an annular chamber adapted to receive the annular front end of a hammer piston, said rearwardly projecting portion of said chuck sleeve adapted to receive and reciprocably guide a tap-pet for transmitting the blows of the hammer piston to the drill steel shank.

10. A water and dirt guard for rock drills, comprising a circular guard body having aligned stepped bores adapted to surround with a close running fit relatively rotatable parts of a rock drill chuck to provide a dirt seal, and having at one end an inwardly directed annular flange adapted to be clamped firmly between relatively adjustable rotatable parts of a drill chuck for rotation therewith.
